UNITED STATES PATENT OFFICE

111,801

DESIGN FOR A DRESS

Jacob Abbate, New York, N. Y.

Application August 23, 1938, Serial No. 79,495

Term of patent 3½ years

To all whom it may concern:

Be it known that I, Jacob Abbate, a citizen of the United States and a resident of the city of New York, in the county of New York and State of New York, have invented a new, original, and ornamental Design for a Dress, of which the following is a specification, reference being had to the accompanying drawing, constituting a part thereof:

Fig. 1 is a front view of a dress showing my new design.

Fig. 2 is a rear view of the dress shown in Fig. 1.

The characteristic feature of my design resides in the combination on the two piece dress disclosed of the specific nailhead embroidery on the top portion as shown.

I claim:

The ornamental design for a dress, substantially as shown and described.

JACOB ABBATE.
